(57) **ABSTRACT**

A new and distinct cultivar of *Leucanthemum* plant named 'Doleuswedaso', characterized by its compact, upright and mounded plant habit; freely branching habit; strong and upright flowering stems; early and freely flowering habit; large single inflorescences with spoon-shaped white-colored ray florets and large central disc; and good garden performance.

1 Drawing Sheet

1

Botanical designation: *Leucanthemum maximum*.
Cultivar denomination: 'DOLEUSWEDASO'.

BACKGROUND OF THE INVENTION

The present invention relates to a new and distinct cultivar of *Leucanthemum* plant, botanically known as *Leucanthemum maximum* and hereinafter referred to by the name 'Doleuswedaso'.

The new *Leucanthemum* plant is a product of a planned breeding program conducted by the Inventor in Aalsmeer, The Netherlands. The objective of the breeding program is to create new compact *Leucanthemum* plants with numerous attractive inflorescences.

The new *Leucanthemum* plant originated from an open-pollination in June, 2014 of a proprietary selection of *Leucanthemum maximum* identified as code number LC13-000287-001, not patented, as the female, or seed, parent with an unknown selection of *Leucanthemum maximum* as the male, or pollen, parent. The new *Leucanthemum* plant was discovered and selected by the Inventor as a single flowering plant from within the progeny of the stated open-pollination in a controlled environment in Aalsmeer, The Netherlands in April, 2015.

Asexual reproduction of the new *Leucanthemum* plant by vegetative terminal cuttings in Aalsmeer, The Netherlands, since May, 2015 has shown that the unique features of this new *Leucanthemum* plant are stable and reproduced true to type in successive generations;

SUMMARY OF THE INVENTION

Plants of the new *Leucanthemum* have not been observed under all possible combinations of environmental conditions

2

and cultural practices. The phenotype may vary somewhat with variations in environmental conditions such as temperature and light intensity, without, however, any variance in genotype.

The following traits have been repeatedly observed and are determined to be the unique characteristics of 'Doleuswedaso'. These characteristics in combination distinguish 'Doleuswedaso' as a new and distinct *Leucanthemum* plant:

1. Compact, upright and mounded plant habit.
2. Freely branching habit.
3. Strong and upright flowering stems.
4. Early and freely flowering habit.
5. Large single inflorescences with spoon-shaped white-colored ray florets and large central disc.
6. Good garden performance.

Plants of the new *Leucanthemum* differ primarily from plants of the female parent selection in the following characteristics:

1. Plants of the new *Leucanthemum* are more compact than plants of the female parent selection.
2. Plants of the new *Leucanthemum* are more freely branching than plants of the female parent selection.
3. Plants of the new *Leucanthemum* are more freely flowering than plants of the female parent selection.
4. Ray florets of plants of the new *Leucanthemum* are spoon-shaped whereas ray florets of plants of the female parent selection are ligulate and not spoon-shaped.

Plants of the new *Leucanthemum* can be compared to plants of *Leucanthemum x superbum* 'Victorian Secret', disclosed in U.S. Plant Pat. No. 22,654. In side-by-side

comparisons, plants of the new *Leucanthemum* differ from plants of 'Victorian Secret' in the following characteristics:

1. Plants of the new *Leucanthemum* are more compact than plants of 'Victorian Secret'. 5
2. Plants of the new *Leucanthemum* are more freely branching than plants of 'Victorian Secret'.
3. Plants of the new *Leucanthemum* have shorter leaves than plants of 'Victorian Secret'.
4. Plants of the new *Leucanthemum* have smaller inflorescences than plants of 'Victorian Secret'. 10
5. Plants of the new *Leucanthemum* are more freely flowering than plants of 'Victorian Secret'.
6. Inflorescences of plants of the new *Leucanthemum* have fewer ray florets and more disc florets than inflorescences of plants of 'Victorian Secret'. 15
7. Ray florets of plants of the new *Leucanthemum* are spoon-shaped whereas ray florets of plants of 'Victorian Secret' are oblanceolate and not spoon-shaped. 20

BRIEF DESCRIPTION OF THE PHOTOGRAPH

The accompanying colored photograph illustrates the overall appearance of the new *Leucanthemum* plant showing the colors as true as it is reasonably possible to obtain in colored reproductions of this type. Colors in the photograph 25 may differ slightly from the color values cited in the detailed botanical description which accurately describe the colors of the new *Leucanthemum* plant.

The photograph is a side perspective view of a typical flowering plant of 'Doleuswedaso' grown in a container. 30

DETAILED BOTANICAL DESCRIPTION

The aforementioned photograph and following observations and measurements describe plants grown in 13-cm 35 containers during the summer in an outdoor nursery in Aalsmeer, The Netherlands and under cultural practices typical of commercial *Leucanthemum* production. During the production of the plants, day temperatures averaged 22° C. and night temperatures averaged 17° C. Plants were 40 pinched one time one week after planting and were three months old when the photograph as taken and four months old when the description was taken. In the following description, color references are made to The Royal Horticultural Society Colour Chart, 2007 Edition, except where 45 general terms of ordinary dictionary significance are used. Botanical classification: *Leucanthemum maximum* 'Doleus-wedaso'.

Parentage:

Female, or seed, parent.—Proprietary selection of *Leucanthemum maximum* identified as code number LC13-000287-001, not patented. 50

Male, or pollen, parent.—Unknown selection of *Leucanthemum maximum*, not patented.

Propagation:

Type.—Terminal vegetative cuttings. 55

Time to initiate roots, summer.—About twelve days at temperatures about 26° C.

Time to initiate roots, winter.—About two weeks at temperatures about 23° C. 60

Time to produce a rooted young plant, summer.—About two weeks at temperatures about 23° C.

Time to produce a rooted young plant, winter.—About 16 days at temperatures about 18° C.

Root description.—Medium in thickness, fibrous; typically white to light brown in color, actual color of the 65

roots is dependent on substrate composition, water quality, fertilizer type and formulation, substrate temperature and physiological age of roots.

Rooting habit.—Moderately freely branching, medium density.

Plant description:

Plant and growth habit.—Herbaceous perennial; compact, upright and mounded plant habit; vigorous growth habit; moderate growth rate; freely branching habit with about 15 primary branches each with about three secondary branches developing per plant.

Plant height.—About 30 cm to 40 cm.

Plant width.—About 26 cm.

Branch description.—Length: About 15 cm. Diameter: About 4 mm. Internode length: About 2 cm. Strength: Strong. Aspect: Erect to about 10° from vertical. Texture and luster: Sparsely pubescent; semi-glossy. Color: Close to 138A.

Leaf description.—Arrangement: Alternate; simple; sessile. Length: About 9.5 cm. Width: About 2.5 cm. Shape: Oblanceolate to oblong. Apex: Rounded to acute. Base: Rounded. Margin: Serrate. Texture and luster, upper and lower surfaces: Smooth, glabrous; matte. Venation pattern: Prominent midvein; reticulate. Color: Developing leaves, upper surface: Close to 137A. Developing leaves, lower surface: Close to 137C. Fully developed leaves, upper surface: Slightly darker than 137A; venation, close to 137A. Fully developed leaves, lower surface: Close to 137C; venation, close to 137C.

Inflorescence description:

Appearance.—Single inflorescence form with spoon-shaped ray florets and tubular disc florets; inflorescences held upright on strong peduncles, inflorescences face mostly upright; ray and disc florets develop acropetally on a capitulum.

Fragrance.—Slightly fragrant, pleasant.

Flowering response.—Plants begin flowering about twelve weeks after planting; plants flower naturally during June and July in The Netherlands.

Postproduction longevity.—Inflorescences maintain good substance for about six to eight weeks on the plant; inflorescences persistent.

Quantity of inflorescences.—Freely flowering habit, about 35 inflorescences develop per plant during the flowering season.

Inflorescence size.—Diameter: About 6.5 cm. Depth (height): About 3 cm to 4 cm. Disc diameter: About 2.2 cm.

Receptacles.—Height: About 7 mm. Diameter: About 2.2 cm. Color: Close to 137D.

Inflorescence buds.—Height: About 5 mm. Diameter: About 1 cm. Shape: Flattened sphere. Color: Close to 137D.

Ray florets.—Quantity per inflorescence: About 42 arranged in a single whorl. Length: About 2 cm. Width: About 6 mm. Shape: Spoon-shaped. Apex: Shallowly emarginate. Margin: Entire; distally, slightly undulate. Aspect: Mostly horizontal. Texture and luster, upper and lower surfaces: Smooth, glabrous; matte. Color: When opening and fully opened, upper surface: Close to 155B; color does not change with development. When opening and fully opened, lower surface: Close to 155D; color does not change with development.

Disc florets.—Quantity per inflorescence: About 400 massed at the center of the receptacle arranged in about twelve whorls. Length: About 6 mm. Diameter: About 1 mm. Shape: Fused tubular. Apex: Acute, five-pointed. Texture and luster, inner and outer surfaces: Smooth, glabrous; somewhat glossy. Color: When opening, inner surface: Close to 14B. When opening, outer surface: Close to 144D. Fully opened, inner surface: Close to 9B; color does not change with development. Fully opened, outer surface: Close to 144D; color does not change with development.

Involucral bracts.—Quantity per inflorescence: About 52 arranged in about three whorls. Length: About 7 mm. Width: About 3 mm. Shape: Oblong. Apex: 15 Obtuse. Base: Fused. Margin: Entire, membranous. Texture and luster, upper and lower surfaces: Smooth, glabrous; somewhat glossy. Color, upper and lower surfaces: Close to 137A.

Peduncles.—Length: About 30 cm to 40 cm. Diameter: 20 About 6 mm. Strength: Strong. Aspect: Upright to about 10° from vertical. Texture and luster: Pubescent; matte. Color: Close to 138A.

Reproductive organs.—Androecium: Present on disc florets only. Quantity per floret: Five per disc floret. 25 Filament length: About 1.5 mm. Filament color:

Close to 3C. Anther shape: Roughly rectangular. Anther length: About 2 mm. Anther color: Close to 14B. Pollen amount: Abundant. Pollen color: Close to 17A. Gynoecium: Present on ray and disc florets. Quantity per floret: One. Pistil length: About 4 mm. Stigma diameter: Close to 1.5 mm. Stigma shape: Bi-parted. Stigma color: Close to 12A. Style length: About 3.5 mm. Style color: Close to 154C. Ovary color: Close to 145C.

Seeds and fruits.—To date, seed and fruit development have not been observed on plants of the new *Leucanthemum*.

Disease & pest resistance: To date, plants of the new *Leucanthemum* have not been observed to be resistant to pathogens and pests common to *Leucanthemum* plants.

Garden performance: Plants of the new *Leucanthemum* have been observed to have good garden performance and to tolerate wind and rain, to tolerate temperatures ranging from -15° C. to 35° C.

It is claimed:

1. A new and distinct *Leucanthemum* plant named 'Doleuswedaso' as illustrated and described.
